US0D1064303S

(12) **United States Design Patent** (10) **Patent No.:** **US D1,064,303 S**
(45) **Date of Patent:** **** Feb. 25, 2025**

(54) **HAIR REMOVAL DEVICE**

(71) Applicant: **Dongguan Boyuan Intelligent Technology Co., Ltd**, Dongguan (CN)

(72) Inventor: **Jinlong Li**, Dongguan (CN)

(73) Assignee: **Dongguan Boyuan Intelligent Technology Co., Ltd**, Dongguan (CN)

(**) Term: **15 Years**

(21) Appl. No.: **29/879,620**

(22) Filed: **Jul. 11, 2023**

(30) **Foreign Application Priority Data**

May 26, 2023 (CN) 202330318705.8

(51) **LOC (15) Cl.** **24-01**

(52) **U.S. Cl.**

USPC **D24/209**

(58) **Field of Classification Search**

USPC D24/133, 209, 210, 158, 200, 231; D26/37-38; D28/44

CPC A45D 26/0009; A45D 26/00; A61B 2018/00476; A61B 2018/0047; A61B 18/20; A61B 18/203
